UNITED STATES PATENT OFFICE.

SYLVESTER SAWYER, OF WOODSTOCK, ONTARIO, CANADA, ASSIGNOR TO
JAMES HAY, SR., AND JAMES HAY, JR., BOTH OF SAME PLACE.

MACHINE FOR SCRAPING AND SPLITTING RATTAN.

SPECIFICATION forming part of Letters Patent No. 284,241, dated September 4, 1883.

Application filed March 5, 1883. (No model.)

To all whom it may concern:

Be it known that I, SYLVESTER SAWYER, of Woodstock, in the county of Oxford and Province of Ontario, Canada, have invented 5 certain new and useful Improvements in Machines for Scraping and Splitting Rattan; and I hereby declare the following specification to be such a full, clear, and exact description of the invention as will enable those skilled in the 10 art to which it appertains to make and use the same.

In the drawings accompanying this description, Figure 1 is a top or plan view of a machine embodying my improvements. Fig. 2 15 is an elevation or side view of the same partially sectioned, as indicated by the plane *u u* of Fig. 1. Fig. 3 is an end view from the left. Fig. 4 is a detail view of the guide-roll which bears the revolving cutter-blades. Fig. 5 is a 20 face view of the knife-head and its supporting-disk. Fig. 6 is a sectional view of the same on the plane *v v* of Fig. 5. Fig. 7 is a section through the knife-head, as indicated by the plane *w w* of Fig. 6. Fig. 8 is a view of the back. 25 Fig. 9 is a detail sectional view of the knife-head, taken along a line, *x x*, of Fig. 5. Fig. 10 is a detail view of the knife-operating hand-slide. Fig. 11 is a cross-section of the stripping or splitting knife support on the plane *y y* of Fig. 1; and Fig. 12 is a cross-section of the pith-catcher 30 on the plane *z z* of Fig. 1, and Figs. 13 and 14 are detail side and edge views of one of the cam-rings.

In these views, A represents the bed-plate 35 which supports the working parts of the machine, and B B are the standards which support this bed-plate. C are the grooved guide-rolls which conduct the rattan sticks through 40 the machine, the shafts of which are connected together and to proper driving mechanism by means of gearing or otherwise, and are acted upon by springs C', which hold the rollers in contact with and permit them to adapt themselves to the various sizes of rattan. D D are 45 the radially-moving scraping-knives, which are actuated by spiral springs D', and are supported by and upon a ring-disk, E. F F are stationary guides, which assist in directing 50 the rattan; and G is the tubular splitting or stripping knife which removes the outer por-

tion of the rattan from the center or pith and splits it into strips, G' being the trough-like guide, which surrounds the cutting end of this knife and collects the strips. These devices 55 are old and well known, and constitute the principal parts of machines of this class and of the kind of machine to which my improvements are especially applicable.

The first of these improvements is a cutting 60 device for squaring the ends of the cane before it is submitted to the scraping and stripping mechanisms. It is best shown in Figs. 1, 3, and 4, and consists of a cutter-plate, B', which is fastened to the upright B² on the end of the 65 bed-plate A, and has an angular opening or cutting-edge, B³, in combination with slanting or beveled cutter-blades C², which are secured to the face of one of the first pair of feed-rolls C, and are arranged in close proximity to the 70 fixed cutter-plate in order that as the rolls C revolve their edges and the edge of the cutter-plate may have a shearing action. The edge of the cutter-plate is angular in shape to prevent the cane from slipping as the revolving 75 blades rise against it. This arrangement also makes a three-sided cut, which lessens the chances of splitting, and results in a squarer end than two chopping-edges can produce; but this edge of the cutter-plate might be of a 80 curved shape and the action would be nearly the same. In front of this cutter-plate is an open guide, B⁴, which conforms in its essential shape to the angle or curve of the cutting-edge B³, and aids materially in feeding the cane to 85 the cutters, for the operator has but to place the end of the cane in the angle or curve of this shelf and push it forward to bring it in the right position to meet the cutter-blades, so that by the assistance of this guide the squaring 90 operation becomes practically automatic and permits the operator to pay exclusive attention to the working of the other parts of the machine.

My second improvement relates to a new 95 form of guide used to accurately present the cane to the scraping-knives. It is seen in the first two figures of drawings, and is composed of two duplicate parts or halves, H H, which are separately pivoted to the bed-plate, and 100 each has a lug, H', upon which lugs a spring, H², bears, thereby causing the halves to close

together. Each half is fitted with a steel facing, H³, which is grooved the better to grasp and direct the cane, and is made removable for the purpose of substituting other facings as one set becomes worn. After the cane has been squared it is inserted in the funnel-shaped receiver or guide on the front end of the machine, and is seized by the guide-rolls C and advanced to the scraping-knives, passing through the guide H just before it reaches the knives. The yielding parts of this guide are separated by the end of the cane, and are equally deflected if its course be straight; but when the cane is bent, or for any other reason deviates from a straight course as it is driven forward, it will impinge upon and deflect one of the parts of the guide more than the other, which causes the more-deflected part to receive the entire pressure of the spring H², thereby relieving the other part.

It will be seen that by this arrangement of the parts of the guide the spring presses equally upon both sides of the cane while it continues in its intended path; and also that as the cane diverges from its proper course the whole resistance of the spring is exerted upon one side of it to return it to its correct position, and all pressure upon its opposite side is removed until such return is accomplished.

More than two parts or members may be used in one guide, and such members may be operated in pairs by different springs, or all may be operated by the same spring.

The third feature of invention and improvement relates to devices operated by hand and devices operated automatically for lifting the knives which do the scraping and holding them apart, in order that the cane may come into place to receive their action; and it also relates to devices for tripping or releasing the knives when the cane is in position to be acted upon. These scraping-knives, preferably, but not necessarily, eight in number, are shown at D, Figs. 1, 2, 5, and 6, being secured in curved recesses in the knife-blocks D², which blocks move radially in beveled grooves D³ in the knife-head D⁴, and are provided upon their spindle ends with spiral springs D', which are arranged to press the knife-blocks inwardly toward the cane. The knife-head D³ is fastened in the central opening of the ring-disk E, rising from the bed-plate, and the outer ends of the knife-blocks pass through guide-posts E' upon the periphery of this disk. Between the knife-head and its supporting-disk is a recess, Figs. 2 and 6, which contains two cam-rings, I I, one superposed upon the other, Figs. 1, 2, 6, and 7, and both arranged to rotate upon friction-rolls E², also supported by said disk E. The bevels or cams I' of one of these cam-rings are inclined in a contrary direction to the bevels of the other ring, Figs. 7 and 13, and these cams bear against the friction-rolls D⁵ on the under side of the knife-blocks, each cam-ring being constructed to carry one-half the number of knives used and to rotate oppositely to the other ring. Projecting forward from these cam-rings are two

posts, I², upon the ends of which bear the longer arms of the elbow-levers J J. These levers are pivoted to blocks J' J', rising from the bed-plate, and their shorter arms bear upon the inner side of the boxes of the shafts which carry the second pair of roll-guides C. The object of these levers is to effect the opening of the scraping-knives D by the closing of the guide-rolls after the passing of the cane. Thus, when a cane leaves these rolls they are closed together by the springs bearing against their shafts, which closing swings the short arms of the levers J toward each other and separates their longer arms, thereby causing the cam-rings I to have a partial rotation, and by forcing their cams under the rolls on the knife-blocks draw the knives back from the path of the cane. As the cam-rings rotate the arms I³ descend, and stops I⁴ on the ends thereof press upon the beveled catches K' on the ends of the sliding bars K, which causes such bars to be drawn out until their catches have been passed by said stops, when the bars are drawn back by the springs K², thus blocking the cam-ring arms, Fig. 7, and holding the knives open. These bars are upon the rear face of the disk E, and move in ways K³, as seen in Fig. 8. Their inner ends close together in the path of the cane, and are provided with beveled grooves K⁴. The scraping-knives being locked in the open position, it will be plain that a new section of cane will separate the roller-shafts, which act upon the levers J, and free their shorter arms, thereby removing the opposition of these levers to the return rotation of the cam-rings and the closing of the knives; also, that as the end of the cane strikes between the beveled ends of the bars K these bars will be moved aside and the cam-arms I³ unlocked, thereby releasing the scraping-knives, which, under the influence of their spiral springs, are closed upon the cane, the cam-rings rotating to their former position at the same time. It being necessary to raise these scraping-knives, or ease them up while they are in contact with the cane, to prevent too deep incisions, or in case of the cane breaking, a second lifting device, which can be operated by the workman, is essential. I show such a device in Figs. 1, 7, and 10, and it consists of wedges L', secured to a forked slide, L, which moves in ways L², and reaches back to the position of the operator at the front of the machine. These wedges are caused to depress the cam-ring arms I³ through the medium of rods L³, the upper ends of which are pivoted to said arms, while their lower ends pass through guides L⁴, fast to the bed-plate, and are provided with friction-rollers L⁵, which run on the inclines of the wedges L', so that pushing the wedges forward draws down the arms of and rotates the cam-rings I, thereby raising the scraping-knives, as already described, but in this case slowly or quickly, a slight distance or entirely away from the cane, as the operator's judgment dictates.

The fourth feature of invention refers to the

relative positions of the edges of the scraping-knives; and it consists, essentially, in arranging the knives so that their cutting-edges shall act upon the cane in different vertical planes; and I effect this arrangement by using cutter-blocks of varying thickness, by adjusting the knives in their curved grooves, or in any of the other many ways that will occur to a person versed in the construction of these machines. Heretofore it has been thought desirable to have the scraping-knives take hold upon the cane all in the same vertical plane perpendicular to the cane, and this was with the intention of securing the substantially simultaneous action of all the knives upon the cane commencing with its extreme forward end; but while this makes it possible for the knives to pass over the entire surface of the cane, the completeness of the scraping does not compensate for the damage to the stock and the trouble incident to the concentrated action of the knives. Thus, as the cane must be driven against the knives with sufficient force to overcome their combined resistance, and when the knives are grouped this resistance being all at one point along the length of the cane, the strain which a brittle or weak stick must meet is often in excess of its strength, and the result is the parting of the stick at one of its joints; or, if the stick be soft, it doubles up in front of the knives, clogging and stopping the machine, and this objection is augmented by the increase of the number of knives in a group, as well as by the proximity of the groups, if there be more than one. Furthermore, the knives of a group act as abutments to hold the cane up against the edges of one another, and thereby they prevent any yielding of the cane under the action of a single knife, so that in the case of joints irregular in their disposition around the cane the shaving on one side of the cane may be too deep and on the other side too shallow. I dispose my knives around the cane in advance of one another in such manner that they act independently upon the joint, and no one knife is opposed by another in the same vertical plane, so that as the cane advances the joints are removed by successive cuttings, instead of at a single operation, and the strain which the cane must meet is distributed along its length; and by this arrangement a certain amount of yielding of the cane under the action of any knife is possible, which greatly lessens the liability of the cane being gouged or unevenly scraped, and for that reason permits a higher velocity of the cane and increases proportionately the production of the machine, besides, by thus improving the operation of the machine, making it more automatic and reducing the necessity of attendance.

The fifth feature of invention has for its object the adjusting of the stripping-knife, which knife is substituted by others when different sizes of cane are being worked, and is occasionally removed for sharpening, and these changes tend to get it out of alignment with

the transmitting devices and make its readjustment necessary. This knife is best shown at G in Figs. 1, 2, and 11, and is of the well-known 70 tubular form, having a circular cutting-edge for separating the center or pith from the outer portion of the cane and radial splitting-edges, which divide such outer portion into strips. The pith passes through the central opening of 75 the knife, and the strips are collected by the guide G' and conveyed away from the machine. G² is a block in which this knife is fastened. It rests upon a sliding wedge, G³, which slides in ways in a block, G⁴, fast to the 80 bed-plate A, but made removable therefrom. To one end of this lower block is fastened a forked or slotted guide, G⁵, which engages with the grooved shank of a screw, G⁶, the threaded end of which enters the knife-block 85 G², so that turning this screw will move the knife-block laterally, and the extended slot in the guide allows it to move vertically. G⁷ is a similar guide and screw for moving the wedge G³ to raise and lower the knife-block, 90 and G⁸ is a set-screw for securing the parts in position when adjusted. In front of this knife-support are the usual guide-rolls, which seize the cane as it comes from the scraping-knives and force it against the splitting-knife, the 95 cane being properly presented to the latter by means of a guide, M, similar to the guide H.

My sixth feature of invention is embodied in a new form of pith-catcher, which receives each of the piths as they are discharged from 100 the machine and places them uniformly in piles, or in some appropriate receptacle located on one side of the general course of the piths to receive them.

Referring to Figs. 1, 2, and 12, N is an up-right frame attached to the delivery end of the machine, and has hinged to it a swinging leaf, O, which is grooved in its lower edge at O', and is fitted with levers O'', to the ends of which are attached springs P, which, being fastened to the frame N, tend to throw the leaf forward, as seen in Fig. 12. Q is a lever pivoted to a block, Q', rising from the bed-plate A, one end of which lever bears upon the outside of the shaft-box of one of the last pair of 110 guide-rolls C and the other end bears against the leaf O. The normal position of these parts is as shown in full lines; but as a pith comes from the stripping-knife and separates the last pair of guide-rolls the longer arm of the lever 115 Q is depressed and swings the leaf O to the position indicated by broken lines, so that as the pith issues from the last guide-rolls it runs along the shelf N' and in the groove O' of the swinging leaf, and the closing of these last 120 guide-rolls after the passage of the pith releases the short arm of the lever Q and allows the springs P to swing the leaf O and the contained pith away from the shelf N', and thereby remove the pith out of the way of the one 125 next following.

Although I have shown and described the yielding guiding or transmitting rolls as actuating the scraping-knives and pith-catcher,

I do not confine myself to them exclusively, as it is manifest that other devices not strictly guides or transmitters might be employed, which, by moving into and out of the path of the cane or pith, would accomplish the same results.

What I claim as new is—

1. The combination, in a rattan-scraping machine, of a beveled revolving cutter-blade 10 and a stationary cutter-plate having an angular cutting-edge, the said blade and plate being arranged to have a shearing action.

2. In combination, in a rattan-scraping machine, a revolving cutter-blade and stationary 15 cutter-plate, substantially as described, and an open angular guide in front of said plate.

3. In a rattan scraping or splitting machine, the combination of a guide composed of two parts constructed to conjointly grasp and direct 20 the cane, and a spring arranged to bear upon both of said parts when they are at rest and equally deflected, and entirely upon either part as it becomes the more deflected, thereby relieving the other.

4. In a rattan-scraping machine, the combination of yielding feeding-rolls, scraping-knives adapted to be withdrawn from the position in which they act upon the cane, and suitable mechanism for automatically retracting 30 said knives, which is operated by the closing of said rolls after the passage of the cane.

5. In a rattan-scraping machine, the combination of two or more scraping-knives arranged to have radial movement, oppositely rotating 35 cam-rings for retracting said knives, and yielding feed-rolls for transmitting the cane through the machine, which are connected with and arranged to operate the cam-rings by the passage of the cane.

6. In a rattan-scraping machine, the combination of scraping-knives having radial movement to and from the position of the cane, a cam-ring for withdrawing said knives, and a sliding wedge arranged to rotate said cam-ring.

7. In a rattan-scraping machine, two or 45 more scraping-knives arranged to completely encircle the cane, the cutting-edges of which each act independently upon the cane at different points along its length; no two edges being in the same vertical plane. 50

8. In a rattan-scraping machine, the combination of scraping-knives arranged to move to and from the cane, two oppositely-rotating cam-rings for raising said knives, and sliding bars the ends of which meet in the path of the cane, said bars being arranged to block the cam-rings for the purpose of retaining the knives in the raised position and to be separated by the end of the cane as it advances for the purpose of releasing the knives from such position. 55

9. In a rattan-stripping machine, a stripping-knife provided with an adjustable support, which is moved laterally by means of a screw moving in a fixed guide, and vertically 60 by means of a wedge moving between such support and a stationary part of the machine.

10. In a rattan-splitting machine, the combination of transmitting rollers or guides, a swinging pith-catcher, and suitable mechanism 70 operated by the pith as it advances for swinging the pith-catcher into position to receive the pith as it is discharged from the machine.

11. In a rattan-stripping machine, the combination of yielding transmitting rollers or guides, a swinging pith-catcher, springs arranged to move such catcher away from the position in which it receives the pith, and suitable mechanism for holding said catcher 80 in the path of the pith, which is arranged to release the catcher upon the closing of the guides as the pith leaves them. 75
